REFRIGERATOR STRUCTURE

Dudley E. Heath, New York, N. Y., assignor to
 Servel, Inc., New York, N. Y., a corporation of
 Delaware

Application May 16, 1940, Serial No. 335,451

3 Claims. (Cl. 20—16)

The present invention relates to door hinges, and more particularly to refrigerator door hinges of the concealed type.

In certain types of refrigerator door constructions, as for instance those of the household type, limitations in the amount of room space usually available renders it desirable to reduce the extent to which the open door juts beyond the hinge side of the box.

With certain types of inset or splay door constructions, the hinge is designed so that only an outer door rim section of reduced thickness juts beyond the hinge side of the box in open position of the door. However, with a substantially full or flush front door construction (that is, a door which extends substantially flush across the full face of the frame bordering the doorway of the refrigerator box), this type of hinge may not always be practical or applicable.

One object of the present invention is to provide a new and improved refrigerator door hinge construction.

Another object is to provide a new and improved refrigerator door hinge construction, in which the extent of projection of the open door beyond the hinge side of the box is reduced to a minimum.

Another object is to provide a new and improved concealed hinge for a refrigerator door of substantially full or flush front construction.

Another object is to provide a substantially full front refrigerator door, having a hinge designed to reduce to a minimum the extent of projection of said door beyond the hinge side of the cabinet, when said door is opened approximately 90°.

Another object is to provide a substantially full front refrigerator door, having a hinge constructed to limit the extent of projection of said door beyond the hinge side of the cabinet, when said door is opened approximately 90°, and having means for hermetically sealing the door in closed position around the outside of the liner or panel openings through which the hinge parts extend.

Among other objects is to provide a new and improved refrigerator door hinge construction, which is simple in construction with a minimum number of parts, which is of extremely practical and rugged construction and not likely to get out of order, and which is well suited to meet the requirements of economical manufacture.

Various other objects of the invention will be apparent from the following particular descrip-

tion, and from an inspection of the accompanying drawing, in which:

Fig. 1 is a front elevation of a refrigerator of the household type, shown with the hinged door open at approximately 90°.

Fig. 2 is a horizontal section through one of the refrigerator door hinge units, embodying the present invention.

Fig. 3 is a section similar to Fig. 2, but showing the door in closed position, and

10 Fig. 4 is a section taken on line 4—4 of Fig. 2. The door hinge construction of the present invention is shown applied to a refrigerator 10 of the household type, comprising a refrigerator storage box 11 having a doorway 12 and a door 13 of double wall construction, hinged to one of the jamb pieces of said box. The refrigerator box 10 has an inner liner 14 and an outer liner 15, separated by suitable heat insulating material 16, and terminating at their front sides in inwardly extending flanges 17 and 18 respectively. Framed around the doorway 12, and extending across the gap between the flanges 17 and 18 is a "breaker" or trim strip 20, made of 15 suitable heat insulating material such as plastic, to heat insulate the inner liner 14 from the outer one 15. For the purpose of firmly mounting the trim strip 20 in position, the rear side thereof has secured thereto by any suitable means, as 20 for instance adhesive, a block 21, desirably made of wood, and extending into a corresponding groove 22 formed in a side post 23. This side post 23 is made of any suitable material such as wood, and is rigidly retained between the inner and outer liners 14 and 15, and against the flanges 17 and 18 as shown.

35 For easy assembly of the trim strip 20, the block 21 has secured thereto a series of fastening members 24, each shown in the form of a double drive screw, with one section thereof firmly embedded in said block, and the other section projecting for fastening engagement with the side post 23. The threads of the projecting section of the screw 24 are steep pitched, so that the trim strip 20 can be secured in position by merely hammering said strip, to drive said screw section into the side post 23.

40 The front face of the refrigerator box 11 around the doorway 12 is shown slightly splayed or slanted, although as far as certain aspects of the invention are concerned, said face may be of square front construction. This slight splaying of the box front assists in the effective sealing of the door in closed position thereof as will be 45 made apparent, and for that purpose, the outer

liner 15 extends forwardly beyond the inner liner 14, and the flange 18 slants inwardly to afford an inclined flat gasket receiving surface 25 in closed position of the door 13, as will be more fully described. The rim section 26 of the flange 18 is shown offset and slightly inclined into co-planar position with respect to the slightly inclined flange 17, so that the trim strip 20 bearing against said flange section 26 and said flange 17 is also slightly inclined.

The inner side portion of the post 23 is desirably provided with a recess 27 to receive the flange 17 therein between said post and the trim strip 20, and the outer side of said post may be similarly provided with a recess 28 for receiving the rim flange section 26 between said post and said trim strip.

The door 13, which is shown substantially of uniform thickness throughout, comprises an inner panel or liner 35 and an outer panel 36, separated by suitable insulating material 37. The outer panel 36 is shown bent around the side edge of the door 13, and terminates in a rim section 38 on the front face of said door in the same plane with the rim section 40 of the inner panel 35. A trim or "breaker" strip 41 of suitable heat insulating material such as plastic is framed over the gap between these panel rim sections 38 and 40. This trim strip 41 is shown supported in position by means of clamping plates 42, fastened to said trim strip by means of screws 43, and bearing against the inner faces of the panel rim sections 38 and 40 by the clamping action of said screws. These panel rim sections 38 and 40 are only slightly inclined as shown to extend the trim strip 41 substantially parallel to the trim strip 20 in closed position of the door 13 as shown in Fig. 3, so that said door is substantially of full or square front construction.

The door hinge construction of the present invention comprises two or more spaced hinge units, each including a pintle 45, supported in a hollow 46 in the hinge side of the door 13 between the panels 35 and 36 thereof, and a hinge leaf or bracket 47, rigid with respect to the refrigerator box 11, and affording a knuckle or bearing 48 loosely embracing said pintle. For affixing the hinge leaf 47 with respect to the refrigerator box 11, said leaf has a flat section 50, extending through an opening 51 in the flange 11, and secured to a flat side of the side post 23 by any suitable means as for instance screws 52. The intermediate portion 53 of the hinge leaf 47 is arcuately curved concentrically with the axis of the pintle 45, and extends through an opening 54 in the inner door panel 35. The hinge leaf section 56 concealed in the door hollow 46 is desirably flat and extends radially of the pintle 45 and of the arc leaf section 53.

For supporting the pintle 45 in fixed position with respect to the door 13, there is provided a bracket 60, shown with a pair of horizontal angular arms 61, interconnected at their ends with wall uprights 62, affixed to spaced sections of the outer door panel 36 by any suitable means as for instance by spot welding. The corner sections of the bracket arms 61 are apertured to receive the ends of the pintle 45, and the knuckle or pintle bearing 48 of the hinge leaf 47 is held for free rotation between said arms.

For hermetically sealing the door 13 in closed position shown in Fig. 3, said door has affixed thereto a sealing strip or gasket 64, adapted to bear against the sealing surface 25 of the liner flange 18 in closed position of said door. This

gasket 64 is shown provided with a tubular section 65, seated on a flat offset section of the door panel 36 adjoining the rim panel section 38, and has a web 67 clamped between the trim strip 41 and said rim section.

The pintle 45 is positioned to move the side 70 of the door 13 inwardly as said door is swung open about said pintle, so that when said door reaches the right angle in open position shown in Figs. 1 and 2, the outer face 71 thereof does not extend its full thickness beyond the outer side of the refrigerator box 11. For that purpose, it is desirable to space the pintle 45 a substantial distance away from the corner 72 of the door. At the same time, the pintle 45 should be positioned, so that the gasket section 65 is free to swing with said door out of sealing position, and without interference from the trim strip 20. With the particular cabinet construction shown, it is found desirable to space the pintle 45 substantially equally distant from the three encircling panel walls of the door.

In closed position of the door 13, the side edge 70 therefore will be substantially flush with the corresponding outer side of the refrigerator box 11 as shown in Fig. 3. As the door 13 is opened, it swings about the fixed pintle 45 and causes the side 70 of said door to move inwardly until said door has been opened approximately 90° in the position shown in Figs. 1 and 2. In this position, the elbow 73 of the hinge leaf 47 will stop further opening movement of the door 13, and the outer door face 11 will be substantially flush with the corresponding outer side of the refrigerator box 11, so that said door in open position will not occupy any more side room than it does in closed position. This advantageous result is effected without sliding link connections, or any movable parts which are apt to get out of order.

It should be noted that in closed position of the door 13, the gasket 64 extends on the outer side of the openings 51 and 54, communicating with the insulating space of the refrigerator box 11 and the door 13 respectively. With the gasket 64 in sealing position as shown, any "breathing" of the air in these insulating spaces in closed position of the door will be between said spaces and the refrigerator storage compartment of the box, so that the undesirable condition of air circulation between these spaces and the air outside of the box is avoided.

As many changes could be made in the above construction, and many apparently widely different embodiments of this invention could be made without departing from the scope of the claims, it is intended that all matter contained in the above description or shown in the accompanying drawing shall be interpreted as illustrative and not in a limiting sense.

Having thus described my invention, what I claim as new and desire to secure by Letters Patent is:

1. In a door mounting, a refrigerator door of a type having spaced apart wall members and extending substantially to the exterior lateral side walls of a body of a refrigerator so as to overlie the front thereof when the door is in its closed position, the inner wall member having an opening, a hinge comprising a stationary strap extending through the opening in said inner wall member and having one end thereof attached to the body of the refrigerator at a region adjacent to one of the exterior lateral side walls, a supporting frame carried by said

door in the space between said wall members, said supporting frame being pivotally mounted upon said strap at a region of the latter in front of and spaced from the body of the refrigerator, the region of said strap at which said supporting frame is pivotally mounted thereon constituting the axis about which said door rotates with respect to the body of the refrigerator, said stationary strap having a curved intermediate part concentric about the axis of rotation of said door, a sealing strip cooperating between the inner side of said door and the body of the refrigerator to form a seal when said door is in its closed position, said sealing strip being so disposed that, when the refrigerator is viewed from the front and said door is in its closed position, the portion of said sealing strip in the vicinity of said hinge lies between said one exterior lateral side wall of the refrigerator and the opening in said inner wall member, the portion of said door between said one exterior lateral side wall and the axis about which said door rotates being freely movable through approximately a right angle toward the front of the refrigerator body when said door is moved from closed to open position, the part of said stationary strap projecting from and in front of the body of the refrigerator determining the extent of movement of said door when moved from closed to open position, and the distance of said axis of rotation from said spaced apart wall members and the peripheral edge portion of said door at said one exterior lateral side wall being such that, when said door is rotated through approximately a right angle from closed to open position, the overall width of the space taken up by the body of the refrigerator and said door is substantially no greater than the distance between the exterior lateral side walls of the refrigerator body.

2. In a door mounting, a refrigerator door of a type having spaced apart wall members and extending substantially to the exterior lateral side walls of a body of a refrigerator so as to overlie the front thereof when the door is in its closed position, the inner wall member having an opening, a hinge comprising a stationary strap extending through the opening in said inner wall member and having one end thereof attached to the body of the refrigerator at a region adjacent to one of the exterior lateral side walls, a supporting frame carried by said door in the space between said wall members, said supporting frame being pivotally mounted upon said strap at a region of the latter in front of and spaced from the body of the refrigerator, the region of said strap at which said supporting frame is pivotally mounted thereon constituting the axis about which said door rotates with respect to the body of the refrigerator, a sealing strip at the inner side of said door, said sealing strip being so disposed that, when the refrigerator is viewed from the front, the portion of said sealing strip in the vicinity of said hinge lies between said one exterior lateral side wall of the refrigerator and the opening in said inner wall member, said sealing strip including the portion in the vicinity of said hinge cooperating with the body of the refrig-

erator to form a seal when said door is in its closed position, the portion of said door between said one exterior lateral side wall and the axis about which said door rotates being freely movable through approximately a right angle toward the front of the refrigerator body when said door is moved from closed to open position, the portion of said sealing strip in the vicinity of said hinge also being movable from the region at which it cooperates with the body of the refrigerator toward the part of said stationary strap projecting from and in front of the body of the refrigerator when said door is moved from closed to open position, so that said door may be moved to its full open position to permit access to the interior of the refrigerator, and the distance between the extreme vertical edge of said door adjacent to said one exterior lateral side wall and the axis of rotation of said door being such that, when said door is moved from closed to open position through approximately a right angle, the overall width of the space taken up by the body of the refrigerator and said door is substantially no greater than the distance between the exterior lateral side walls of the refrigerator body.

3. In a door mounting, a refrigerator door of a type having spaced apart wall members and extending substantially to the exterior lateral side walls of a body of a refrigerator so as to overlie the front thereof when the door is in its closed position, a hinge comprising a stationary strap having one end thereof attached to the body of the refrigerator at a region adjacent to one of the exterior lateral side walls, a supporting frame carried by said door in the space between said wall members, said supporting frame being pivotally mounted upon said strap at a region of the latter in front of and spaced from the body of the refrigerator, the region of said strap at which said supporting frame is pivotally mounted thereon constituting the axis about which said door rotates with respect to the body of the refrigerator, a sealing strip at the inner side of said door, said sealing strip being so disposed that, when the refrigerator is viewed from the front, the portion of said sealing strip in the vicinity of said hinge lies between said one exterior lateral side wall of the refrigerator and a part of said stationary strap projecting from and in front of the body of the refrigerator, said sealing strip including the portion in the vicinity of said hinge cooperating with the body of the refrigerator to form a seal when said door is in its closed position, the portion of said door between said one exterior lateral side wall and the axis about which said door rotates being freely movable through approximately a right angle toward the front of the refrigerator body when said door is moved from closed to open position, the portion of said sealing strip in the vicinity of said hinge also being freely movable from the region at which it cooperates with the body of the refrigerator toward the part of said stationary strap projecting from and in front of the body of the refrigerator when said door is moved from closed to open position, so that said door may be moved to its full open position to permit access to the interior of the refrigerator.

DUDLEY E. HEATH.
